UNITED STATES PATENT OFFICE.

JOHN BAKER, OF BROOKLYN, NEW YORK.

BOAT-PROPELLING MECHANISM.

Application filed February 11, 1927. Serial No. 167,549.

This invention relates to boat propelling devices and has special reference to an improvement on the boat propelling device shown and described in my prior application for Patent Number 1,551,360, granted to me August 25, 1925.

One important object of the invention is to improve the general construction of devices of this character.

10 A second important object of the invention is to provide an improved device of this character wherein the driving means will be actuated by the operation of a pair of levers in a manner precisely similar to the 15 operation of a pair of ordinary oars.

A third important object of the invention is to provide an improved sprocket chain drive for devices of this class.

With the above and other objects in view 20 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a longitudinal section through 30 a boat showing one side thereof equipped with the invention.

Figure 2 is an enlarged cross section of the boat on the line 2—2 of Figure 1.

Figure 3 is an enlarged plan view of one 35 of the devices.

Figure 4 is a side elevation of such device with a certain bearing bracket broken away to show the parts behind the same.

Figure 5 is a detail view showing how an 40 ordinary stern propeller may be used in connection with the device.

For the purpose of illustrating the invention there has here been disclosed a boat B of conventional form and it will be seen 45 from an inspection of Figure 2 that one of these devices is attached to the boat on the inner face of each side. Each of the devices, in the embodiment here shown, consists of a base 10 by which it is secured to the boat 50 side. On the inner side of each base there is mounted a U-shaped bearing bracket 11 preferably of heavy strap iron and fixed in the base is a bearing bushing 12 for the reception of a shaft 13 having reduced ends 55 which fit this bushing and in a suitable opening in the bracket 11. On this shaft is a

sprocket wheel 14. Similarly, at the other end of the base there is provided a bearing bushing 15 and a shaft 16 is journaled in the bracket 11 and in the bushing 15 to project 60 beyond the bushing as shown at 17, the boat side having an opening at this point to permit the shaft to pass therethrough. This projecting shaft end 17 carries a paddle wheel or propeller 18. In the form shown 65 in Figure 5 it will be seen that the shaft 17 may be geared to a longitudinally extending shaft 19 supported in a bearing bracket 20 and carrying a standard screw propeller 21, the gearing connection being by means of beveled gears 22. Thus, either a paddle propeller or screw propeller may be used with the invention. On the shaft 16 is fixed a sprocket 23 which is connected by a sprocket chain 24 with the sprocket 14. Adjacent the 70 shaft 16 the base is provided with still another bearing bushing 25 and a shaft 26 is journaled in this bushing and in the bracket 11. On this shaft 26 is mounted a fly-wheel 27 to which is fixed a sprocket 28 engaged 75 by the chain 24 so that movement of this chain revolves the sprocket 28 and drives the fly-wheel. Fixed to the inner side of the base 10 is a pair of brackets 29 which support idler pulleys 30 arranged in pairs with 80 the planes passing through the axes of the pairs inclined downwardly away from each other so that the pulleys may be said to be positioned at the angles of a trapezoid. The two upper pulleys are arranged close to the 85 upper run of the chain 24 and over the four pulleys passes a sprocket chain 31, the upper run of which is parallel to and close against the underside of the upper run of the chain 24. Each of the links of the chain 31 carries 90 a long tooth 32 which projects up through the links of the chain 24 in passing along the upper run of the chain 31 and gradually moves into and out of the projecting position by reason of the inclination of the pairs of pulleys.

95 Fixed on the inner side of the bracket 11 opposite the upper run of the chain 31 is a bracket 33 whereon is mounted for movement about a vertical axis a ball and socket joint 34 whereof the ball carries the outboard arm 35 and the inboard arm 36 of an oar like lever terminating inwardly in a handle 37. The outboard arm 35 is shaped to fit between 100 the teeth 32 in their upwardly projecting positions and it will be seen that by operating the lever after the fashion of an oar 110

the arm 35 engages the teeth 32 and moves the chain 24 so that its upper run moves in a forward direction. It will also be seen that this lever is automatically released from 5 the teeth 32 as they move downwardly out of projected position. Obviously, as the chain 24 is thus moved the fly-wheel 27 will be rotated and the shaft 17 will be likewise rotated so that the propeller will be driven. 10 Thus, by pulling on the oar like lever in the usual manner common to such devices the boat is driven ahead, the fly-wheels on the two sides storing up energy and delivering the same during the return strokes of the 15 levers.

There has thus been provided a simple and efficient device of the kind described and for the purpose specified.

It is obvious that minor changes may be 20 made in the form and construction of the invention without departing from the material spirit thereof. It is not, therefore, desired to confine the invention to the exact form herein shown and described, but it is 25 desired to include all such as properly come within the scope claimed.

Having thus described the invention, what is claimed as new, is:

1. In a boat propelling mechanism, an 30 endless chain arranged for operative connection to a boat propeller, a second endless chain adjacent the first and having spaced fingers, said chains being arranged to cause the path of one chain to approach and recede from one portion of the path of the other chain and thereby cause the fingers to project through the links of the first chain, and an oscillatory lever fulcrumed adjacent the 35 chains and having an end positioned to engage the fingers projecting through the first chain to move said chains.

2. In a boat propelling mechanism, a pair 40 of spaced sprocket wheels, an endless chain carried by said sprocket wheels, a shaft whereon one of said sprockets is fixed and constituting a propeller drive shaft, a second 45 endless chain, wheels over which said second chain runs, two of said last wheels being close to one portion of the path of the first 50 chain to cause a portion of the path of the second chain to lie parallel to the corresponding portion of the first path and adjacent thereto, fingers carried by the second chain and projecting through the links of 55 the first chain during their passage along the portion of the second chain path adjacent the first chain path, and an oscillatory lever fulcrumed adjacent said chains and having an end engaging the fingers upon their projection 60 through the first chain.

3. In a boat propelling mechanism, a pair 65 of spaced sprocket wheels, an endless chain

carried by said sprocket wheels, a shaft whereon one of said sprockets is fixed and constituting a propeller drive shaft, a second 70 endless chain, wheels over which said second chain runs, two of said last wheels being close to one portion of the path of the first chain to cause a portion of the path of the second chain to lie parallel to the corresponding portion of the first path and adjacent thereto, fingers carried by the second chain and projecting through the links of the first chain during their passage along the portion of the second chain path adjacent the first chain path, a lever having an end 75 adapted to engage the fingers upon their projection through the first chain, and a universally jointed fulcrum supporting said lever adjacent the chains.

4. In a boat propelling mechanism, a pair 80 of spaced sprocket wheels, an endless chain carried by said sprocket wheels, a shaft whereon one of said sprockets is fixed and constituting a propeller drive shaft, a second 85 endless chain, wheels over which said second chain runs, two of said last wheels being close to one portion of the path of the first chain to cause a portion of the path of the second chain to lie parallel to the corresponding portion of the first path and adjacent thereto, fingers carried by the second chain and projecting through the links of the first chain during their passage along the portion of the second chain path adjacent the first chain path, a lever having an end 90 adapted to engage the fingers upon their projection through the first chain, and a fly-wheel driven by the first chain.

5. In a boat propelling mechanism, a pair 95 of spaced sprocket wheels, an endless chain carried by said sprocket wheels, a shaft whereon one of said sprockets is fixed and constituting a propeller drive shaft, a second 100 endless chain, wheels over which said second chain runs, two of said last wheels being close to one portion of the path of the first chain to cause a portion of the path of the second chain to lie parallel to the corresponding portion of the first path and adjacent thereto, fingers carried by the second chain and projecting through the links of the first chain during their passage along the portion of the second chain path adjacent the first chain path, a lever having an end 105 adapted to engage the fingers upon their projection through the first chain, a universally jointed fulcrum supporting said lever adjacent the chains, and a fly-wheel driven 110 by the first chain.

In testimony whereof I affix my signature.

JOHN BAKER.
